United States Patent Office

Des. 211,681
Patented July 9, 1968

211,681

KNIFE OR SIMILAR ARTICLE

Richard Hopcraft, Providence, R.I., assignor to Imperial Knife Associated Companies, Inc., New York, N.Y., a corporation of Rhode Island

Filed Aug. 10, 1967, Ser. No. 8,213

Term of patent 14 years

(Cl. D95—3)

FIG. 1

FIG. 2

FIG. 3

FIG. 1 is a left side elevational view of a knife showing my new design;

FIG. 2 is a front elevational view;

FIG. 3 is a right side elevational view;

FIG. 4 is a rear elevational view; and

FIG. 5 is an elevational view from the bottom of FIG. 1.

The dominant features of the design are shown in full lines.

I claim:

The ornamental design for a knife or similar article, substantially as shown and described.
